AUTOMATIC GRAPH REPRODUCING DEVICE

Egon Darnhofer, Vienna, Austria

Application August 22, 1929, Serial No. 387,727,
and in Austria August 31, 1928

14 Claims. (Cl. 33—18)

This invention relates to a device for automatically and repeatedly reproducing drawings, writings and the like which has to satisfy two objects, firstly to produce a stencil of the drawing or the like and secondly to reproduce by way of this stencil the drawing or the like as often as desired. In order to produce the stencil, when drawing or following the lines of the drawing or writing, the device divides the movement carried out thereby into two partial movements and transfers the same to a continuously moving band in such a manner, that the same can be used for reproducing the same partial movements, which again are combined to produce the correct movement of the pencil.

The particular auxiliary means for attaining this object form the subject matter of the present invention.

By means of the device it is possible to fix drawings or writings during their production or subsequently by following their lines in such a manner, that they can be repeatedly reproduced at any time.

A device constructed according to the present invention is illustrated diagrammatically and by way of example in the drawing.

A cylinder 8 is mounted between two lateral supports 16—16 and provided with a straight narrow groove 9, which extends parallel with respect to the axis of the said cylinder. Two sliding rods 12 and 13 are slidably mounted in the supports and extend parallel with respect to the cylinder 8. An arm 10, fixed to the rod 12, and an arm 11, rigidly secured to the rod 13, serve as holders of pins 6 and 7 respectively, the points of which extend into the groove 9 of the cylinder 8 and move along the same in case the sliding rods 12 and 13 are shifted. Screw-shaped torsion and pressure springs 14 and 15 are arranged on the rods 12 and 13 in such a manner, that they have the tendency to continuously force the pins 6 and 7 into the groove 9 and towards the middle of the cylinder 8. One end of each spring is secured to its rod, while the other end thereof is fixed to the corresponding support 16.

By means of a rope or band, passing round a roller 17 and secured to the rod 12, the said rod 12 is connected with the roller 17 (which is rotatable around the geometric axis 2—2 and mounted on a shaft 20) in such a manner, that a forward and backward rotation of the roller 17 corresponds to each to and fro movement of the rod 12. Also the sliding rod 13 is connected with a circular arched arm 18 of the support 19 in such a manner, that a to and fro movement

of the rod 13 results in a corresponding forward and backward rotation of the support 19. The latter is rotatably mounted in the top of a table (not illustrated) by means of a ball bearing. A drawing sheet *a—b—c—d* is mounted on the top of said table.

The shaft 20 rigidly connects the roller 17 with a disc 21 and is centrally mounted in a ball-bearing of the support 19, so that the latter as well as the shaft 20 with the roller 17 and the disc 21 are rotatable independently of one another around the axis 2—2. The ends of the support 19 are provided with bearings 22 for the attachment of a reciprocating rod 23. This reciprocating motion is transmitted to the disc 21 in the same way as is the case in connection with the transmission of the movement from the sliding rod 12 to the roller 17 and from the sliding rod 13 to the arm 18 of the support 19. In view of this arrangement each movement of the rod 12 results in a corresponding sliding motion of the rod 23, this taking place to an extent which depends on the proportion between the diameters of the roller 17 and the disc 21. The drawing-pin holder 24 is mounted on the rod 23 by means of two eyes 34, and thus the former can turn about the rod 23. However a stop and screw at the outer end of the sliding rod 23 secure the said holder 24 against movement in its longitudinal direction.

The end of the drawing-pin holder 24 is slightly bent to the side and carries the drawing pin 1. Between the eyes 34, the drawing-pin holder 24 is bent in such a manner, that the part 35—35 extends parallel to the sliding rod 23 and thus intersects the geometric axis 2—2. Here the part 35—35 of the holder 24 passes through the forked end 33 of a lever 31 which, by means of its bearing-pins 30, is mounted in the frame of the device (not illustrated). The other end of this lever is enlarged and forms the armature 32 of an electromagnet 29. One end of the latter is connected to a source of current, while the other end of the electromagnet is connected to a rod 25, which is mounted non-rotatable and insulated in the supports 16. A contact spring 26 is fixed to the rod 25 and rests on the cylinder 8, which consists of an electrical conducting material. The electric circuit is completed by a wire passing from the cylinder 8 to the source of current.

A key-lever 36 is rotatably mounted on the rod 25 and provided with a pin 37, which is continuously pressed onto the cylinder 8 by a spring 38. The pin 37 can be lifted away from

110

the cylinder 8 by depressing the key 39 of the lever 36.

A small toothed wheel, the teeth 42 of which project out of the cylinder 8, is centrally and freely rotatable mounted in the cylinder 8 (not illustrated in the drawing).

This device operates in the following manner, when producing a stencil from a drawing or writing.

- 10 If a line is drawn or a drawn line is followed by the pencil 1 on the drawing sheet *a e f g*, arranged on the area *a b c d* adapted to be traversed by the said pencil, the sliding rod 23 will be longitudinally shifted as well as turned about 15 the geometric axis 2—2 and further these two component movements are separately transmitted. The longitudinal movement of the rod 23 is transmitted to the disc 21 by means of the band connecting the two parts and the disc is 20 turned. However this turning motion is transformed again into a straight sliding motion of the sliding rod 12 by means of the shaft 20 and the roller 17, because the latter and the rod 12 are connected with each other in the same way 25 as the disc 21 and rod 23. The longitudinal movement of the rod 12 is transmitted to the pin-holder 10 fixed to the said rod and to the pin 6. A band or tape 3 is slowly and uniformly drawn over the fixed cylinder 8, in order to permanently 30 secure the to and fro movements of the pin 6, produced during the drawing or copying of a number of lines. The band or tape 3 is, for instance, wound up on a roller (not illustrated), which is subjected to a slight braking 35 action, and passes by way of the cylinder 8 to another roller. The winding off operation can be carried out by hand or by a spring or electrically operated mechanism. The perforation 41 of the band or tape 3 are engaged by the 40 teeth of the toothed wheel 42, projecting out of the cylinder 8, in order to insure an exact lateral guidance on the roller. During the uniform feed of the band 3, the movements of the pin 6 are traced on the latter in the shape of a curve or 45 slight cut 4.

In a similar way each turning movement of the sliding rod 23 around the geometric axis 2—2 is transmitted to the sliding rod 13 by means of the bearings 22 of the support 19 and its arm 18, 50 because the said rod 13 is also connected with the circular arched end of the arm 18 by means of the band. Thus during every turning motion of the sliding bar 23, the pin-holder 11 and consequently its pin 7 carry out a lateral movement 55 with respect to the sliding rod 13, and this lateral movement is traced on the band or tape 3 in the shape of a line or slight cut 5.

However drawings, writings and so forth do not consist of a single uninterrupted line, and therefore the drawing-pin 1 has to be guided from the end of one line to the beginning of the next line without touching the drawing surface. Also these auxiliary movements of the drawing 65 pin have to be rendered visible on the stencil, because the band 3 is uniformly fed during that time and also these auxiliary movements of the drawing-pin are copied. The key-lever 36 with the pin 37 serves for this object. When drawing 70 or following a line with the drawing-pin 1, the pin 37 is lifted away from the band 3 by depressing the key 39 by hand. If the drawing-pin 1 is lifted off of the drawing sheet at the end of a line for carrying out the auxiliary movement, the key 75 39 is released and the spring 38 now forces the

pin 37 onto the band 3 and the latter draws a line on or slightly cuts at 40 the said band.

The movements of the drawing-pin 1 are in this way divided on the two borders of the band 3 into radial and into turning movements and copied in the form of two curves 4 and 5 according to a size determined by the proportion of the construction of the device. If the band 3 is fed again in the same direction as before through the device and if thereby the pins 6 and 7 are moved exactly over the two marginal curves 4 and 5, the drawing-pin 1 is compelled to again carry out the same movements as it has been previously the case during the production of the drawing (during the following of the drawing) and of the curves 4 and 5. The two borders are cut away along the curves 4 and 5, in order to render unnecessary the tracing by hand of these curves by the aid of the pins 6 and 7. Now if this band passes over the roller 8, whereby it is exactly laterally guided by the cooperation between the perforations 41 and the toothed wheel 42, the pins 6 and 7 can engage the groove 9 of the cylinder 8 in consequence of the rotary action of the springs 14 and 15, and the said pins 6, 7 are forced onto the curved edges of the band 3 by the action of the said springs and consequently exactly follow the course of the curves during the feed of the band 3.

The following arrangement is provided if it be desired, that the drawing pin 1 is automatically raised from the drawing surface in case it does not actually draw a line but carries out an auxiliary motion. Two overlapping rows of perforations 27, which are staggered with respect to each other, are arranged along the band 3, the said rows of perforations being interrupted at all those places where the adjacent line 40, produced by the pin 37, is interrupted. However, if desired, the rows of perforations may be uninterrupted and covered with paper at the said places. The two ends of the contact-spring 36 alternately pass through the said double row of perforations and engage the roller 8, so that the latter always cooperates with one of the said two ends. Thus 120 the current circuit is closed by way of the source of current, the roller 8, contact-spring 36, the insulated rod 25, the wire 28, the electromagnet 29 and the other wire 28, connected to the source of current. The circuit is closed in case of an 125 interrupted or covered row of perforations, as long as a row of perforations 27 (or an uncovered place of the row of perforations) passes below the contact-spring 26 during the feed of the band 3 over the cylinder 8. Therefore every time a part 130 of the row of perforations 27, corresponding to the lines 40 of the band 3 (thus to the auxiliary movements of the drawing-pin 1), passes over the cylinder 8, the electromagnet 29 attracts its armature 32 and consequently tilts the lever 31 and 135 slightly lifts the forked end 33 of the latter. The latter operates the drawing-pin holder 24 and turns the same about its two eyes 34, whereby the pin is lifted away from the drawing surface. Thus, during the production of the stencil, if the 140 drawing-pin 1 has carried out an auxiliary movement, the same idly passes over the drawing surface during the reproduction of the drawing or writing by means of the stencil, until the current is interrupted each time at the ends of the rows 145 of perforations 27, the electromagnet 29 releasing the armature and the pin 1 by its own weight and the weight of the holder 24 again cooperates with the drawing surface in order to draw or follow a new line.

A double row of perforations 27 has to be provided for the following reason. During the whole course of a line 40, the pin 1 has to be lifted away from the drawing surface and therefore the current circuit must not be interrupted. The band 3 would loose its lateral connection in view of the sometimes considerable length of the lines 40 and thus the necessity of slits, if it would be the intention to attain the said object by a single slit and a single contact-spring 26 passing therethrough. Therefore for the sake of strength, this slit has to be interrupted by webs and consequently a second row of slits has to be provided, which compensates the said interruptions by webs. Thus the slits have to be displaced with respect to one another and further they should slightly overlap one another in order to provide for an uninterrupted current circuit by means of the two contact-springs 26, alternately passing through the band 3.

The accuracy of the reproduction can be controlled by varying the speed of travel of band 3 for a given travel of stylus 1, that is, by varying the ratio between the two rates of movement.

The drawing area *a e f g* may consist of a transparent material on which is written or drawn with opaque or colored transparent material. It may be rendered opaque by a coat of very fine sand, soot, lamp-black or the like, which the drawing-pin 1 obliterates, wipes off or scrapes off during its movement, so that light lines will appear on a dark ground.

The same drawing but in a reversed sequence of lines and order, which is adapted for advertisements or announcements, is produced if the stencil passes in the reversed direction through the device in the event of reproducing a drawing.

The movements carried out by the pins 6 and 7, when copying a drawing by means of the pencil 1, can be converted into fluctuations of current which, in known manner, can be transmitted to any place either by wire or by wireless. The receiver can use these fluctuations of current either for drawing the two lines 4 and 5 on a strip 3 or, in the case of a corresponding slower transmission and sufficiently strengthened receiving current, the same can be used also for controlling the suitably constructed reproduction device. Thus a drawing or writing carried out or followed by the pencil 1 can be simultaneously reproduced by the receiver arrangement. Complete stencils 3 can be transmitted by wireless.

I claim:—

1. Device for dividing the movements following the lines of drawings, writings and the like into two partial movements and transmitting the latter to a stencil for repeatedly reproducing the same from said stencil, comprising in combination a lever, bearings on the lever, a rod slidably arranged in said bearings, a drawing pencil connected with said sliding rod, a shaft passing through said lever, a disc on the shaft in operative turning engagement with the sliding rod, the longitudinal movement of the sliding rod being converted into opposite rotations respectively of said disc, a roller secured to said shaft, a slotted extension secured to said lever and adapted to receive turning motion from the latter, a pair of parallel positioned pins, means for transmitting and converting the movements of said roller and slotted extension into straight transverse movement in the respective parallel pins, and a uniformly fed band operated on by the said pins.

2. Device for dividing the movements follow-

ing the lines of drawings, writings and the like into two partial movements and transmitting the latter to a stencil for repeatedly reproducing the same from said stencil, comprising in combination a lever, bearings on the lever, a rod slidably arranged in said bearings, a drawing pencil connected with said sliding rod, a shaft passing through said lever, a disc on the shaft in operative turning engagement with the said sliding rod, the longitudinal movement of the sliding rod being converted into respective directions of rotation of said disc, a roller secured to said shaft, a slotted extension secured to said lever adapted to receive turning motion from the latter, a sliding rod in engagement with said roller, a pin secured to this sliding rod, another sliding rod in engagement with said slotted extension, a pin secured to the sliding rod last mentioned, a cylinder underneath the said pins, there being a groove in said cylinder wherein the said pins operate.

3. Device as claimed in claim 1 in which the pins mark the two components of each movement on the band in order to form a stencil.

4. Device for dividing the movements following the lines of drawings, writings and the like into two partial movements, comprising in combination a uniformly fed stencil, pins cooperating with said stencil, a roller to which the movement of one of said pins is imparted, a lever provided with an extension to which the movement of the other pin is transmitted, a disc connected with said roller, a sliding rod in operative engagement with said disc, a lever in which said rod is slidably arranged, a connection between the second pin and said lever and a drawing pencil connected with said sliding rod.

5. Device as claimed in claim 1 further comprising a drawing-pencil holder mounted on the sliding rod, a part of the holder extending parallel to said sliding rod, and a lever engaging the said holder.

6. A reproducing device for actuating a pencil to draw a graph consisting of a continuous or interrupted line comprising a matrix formed by a band, the opposite edges of which control the movements of the pencil and correspond to the respective components of the points on the graph executed by said pencil.

7. A device as claimed in claim 1 in which the uniformly fed band has its marked edges removed, and means for urging each parallel pin against its respective edge to automatically follow along said band edges for the purpose of operating the pencil and reproducing a graph.

8. A device for writing characters, comprising, in combination with a writing member, a strip-shaped control member, the edges of which are curved corresponding to the components of the characters to be written down.

9. A device for writing characters, and the like, comprising, in combination with a writing member, a strip-shaped control member, the edges of which are curved corresponding to the components of the characters to be written down, and which has longitudinal rows of perforations, and means adjacent said strip co-acting with said perforations to lift and lower in turn said writing member.

10. A device for writing characters, and the like, comprising, in combination with a writing member, a strip-shaped control member, the edges of which are curved corresponding to the components of the characters to be written down, a device controlled by one edge of said control-

- member; an axle connected with said device; an arm extending from said axle for moving said writing member in the direction of one of the two components; a rod slidingly combined with said 5 arm and being connected with the said writing member and adapted to move it in the direction of the other component, and means connecting said rod to be controlled by the other edge of said control-member.
- 10 11. A device for writing characters, and the like, comprising, in combination with a writing member, a strip-shaped control member, the edges of which are curved corresponding to the components of the characters to be written, an axle, 15 an arm extending from said axle; and being connected with said writing member, a rod arranged in said arm and being longitudinally shiftable therein and connected at its free end with said writing member; means for holding this latter in 20 operative position, said arm being turned in dependency of one of said components and said rod being shifted in dependency of the other of the said components, substantially as set forth.
12. A device for writing characters and the 25 like comprising, in combination with a writing member, a strip-shaped control member, the edges of which are curved corresponding to the
- 30 components of the characters to be written down, said strip-shaped control member having perforations therein, and a toothed disk, the teeth of which engage the perforations of the strip-shaped control member. 80
13. Mechanism for writing characters comprising, a writing member, a strip-shaped control member having curved edges corresponding to the components of the characters to be written down, devices having elements thereon in engagement with the edges of said strip-shaped control member, and means associated with said devices for transmitting the movement of the devices to the writing member. 85
14. A device for writing characters comprising, a writing member, a strip-shaped control member having curved edges corresponding to the components of the character to be written down, devices having elements thereon in engagement with the respective edges of the strip-shaped control member, means associated with said devices for transmitting the movement of the levers to the writing member, and means for preventing lateral deviation of the strip-shaped control member. 90
